UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,341,753.

Specification of Letters Patent.

Patented June 1, 1920.

Application filed May 16, 1917. Serial No. 168,946.

To all whom it may concern:

Be it known that I, LLOYD V. LEWIS, a citizen of the United States, residing at Edgewood borough, in the county of Allegheny and State of Pennsylvania, have invented certain new and useful Improvements in Railway-Traffic-Controlling Apparatus, of which the following is a specification.

10 My invention relates to railway traffic controlling apparatus, and particularly to apparatus for controlling the speed of railway trains or cars.

I will describe one form of apparatus embodying my invention, and will then point out the novel features thereof in claims.

15 In the accompanying drawings, Figure 1 is a view showing in side elevation one form of apparatus embodying my invention. Fig. 2 is a diagrammatic view showing a railway signaling system including one form of trackway apparatus embodying my invention.

Similar reference characters refer to similar parts in each of the views.

20 Referring to the drawings in detail and particularly to Fig. 1, A designates one of the track rails of a railway over which traffic normally moves in the direction indicated by the arrow. Suitably mounted on a vehicle, such as a locomotive or a car, is a casing D which is provided with a longitudinally extending bore 10, the upper end of which bore is closed, and a transverse bore 11 intersecting the bore 10, as shown. Slidably mounted within the bore 10 is an operating bar E which extends through a slot 12 formed in a bar F slidably mounted in the bore 11. The slot 12 is disposed diagonally with respect to the bar F to provide cam surfaces 13 and 13^a, which cam surfaces are at times engaged by similarly arranged cam surfaces 14 and 14^a respectively of a cam 15 formed in the bar E, to impart longitudinal movement to the bar F when the bar E is moved vertically within the bore 10. That is to say, bar F is moved to the left or right, according as the bar E is moved upward or downward. The bar E is biased to a projected position as shown by means of an expansible spring 16 arranged between the bar and the upper end of casing D. Spring 16 is guided by a rod 17, secured to the upper end of the bar and passing

freely through an opening formed in the 55 casing. A contact shoe 18 is secured to but insulated from the lower end of the bar E, and is in electrical contact at all times with a spring contact finger 19 secured to but insulated from the casing D. 60

To impart vertical movement to the bar E and to conduct current to the vehicle governing apparatus as will be described hereinafter, the contact shoe is adapted to engage conducting trips T and T' located in 65 the trackway. As here shown, the trips are stationary and are disposed within the path of travel of the contact shoe 18, so that they will be successively engaged by the contact shoe of a passing vehicle. Each trip T is 70 formed with an anticlinal working surface whereby the contact shoe 18 will be caused to ride upwardly thereon, thus moving the bar E vertically against its biasing means and thereby moving the bar F to the left 75 from the position shown in the drawing.

As here shown, the vehicle's travel along the track is governed by means of a valve V arranged at one end of a pipe 20, such valve controlling the exhaust of air from the pipe 80 to control the brake apparatus in a manner well understood in the art. The valve V is operated by bar F through the medium of a bell crank 21 and a lever 22 pivoted at one of its ends to the bell crank while its opposite end is engageable with a shoulder 23 formed on the left-hand end of the bar F. The lever 22 may be moved into or out of the path of movement of the shoulder 23 by means of a solenoid M, such lever passing 85 freely through the lower end of the movable portion of the core of such solenoid. When the solenoid is energized, lever 22 is lifted out of the path of the bar F so that movement of such bar is ineffective to open 90 the valve V. However, when the solenoid is deenergized, lever 22 gravitates into the path of bar F so that when the bar is moved to the left, shoulder 23 engages the lever and thus actuates the same to open the 95 valve V and to thereby cause the brakes of the vehicle to be applied. It will thus be seen that the bar F is effective or ineffective to cause the brakes to be applied, according as the solenoid M is deenergized or energized. 100

At this point, I desire to point out that in order to simplify the drawings, I have

not shown complete circuits throughout, but have, in certain instances, shown only the portions of the circuits which pass through the apparatus included in the drawings; the 5 remaining portions of the respective circuits being indicated either by the letter B or C; B indicating battery wire and C indicating common return wire.

Connected in multiple with the solenoid 0 M is a second solenoid M' which controls a valve V' to admit fluid pressure to a whistle W from a pipe Z. The control of the valve V' is such that the whistle W is blown only when the solenoid M' is deenergized. The 15 circuits for the solenoids M and M' are controlled by an armature r of a relay R, such relay being of the slow pickup type. Relay R is provided with a "main" circuit which is controlled by a circuit controller generally 20 indicated at G and which comprises a pair of contacts 24 and 24^a, and a bridging member 25, the latter being secured to and insulated from the right-hand end of the bar F. This main circuit is as follows: from battery wire 25 B through contact 24, bridging member 25, contact 24^a, wires 30 and 31, relay R and common return wire C back to battery. It will be seen therefore that the bridging member 25 connects or disconnects the contacts 24 and 24^a to open or close the main circuit according as the bar F occupies its retracted or projected position. Relay R is provided with a secondary circuit which is controlled by a relay R' through its contact 30 35 r'. The secondary circuit is from battery wire B, through wire 32, contact r', wire 31, relay R, and common return wire C back to battery. One terminal of relay R' is grounded through the frame of the vehicle, 40 while the other terminal thereof is electrically connected to the contact finger 19 by a wire 26. Relay R' is provided with another contact r^a which controls the circuit for a second slow acting relay R'', this relay, 45 however, being of the slow release type. This circuit may be traced as follows: from battery wire B, wire 33, contact r^a, wire 34, relay R'', and common return wire C back to battery. The relay R'' in turn controls 50 through its contact r'', an auxiliary circuit for relay R so that such relay is maintained energized even in the event of an imperfect contact between the contact shoe 18 and the trips T or T', as will be more fully explained 55 hereinafter. This auxiliary circuit is from battery wire B, through contact r'', wires 35 and 31, relay R, and common return wire C.

Located in the trackway are sources of 60 current 27 and 27^a for the trips T and T' respectively. One terminal of each source of current 27 or 27^a is grounded as shown, while the other terminal is at times connected with the corresponding trip T or T' by a 65 wire 28 or 28^a, which wire is connected to

or disconnected from the source of current 27 or 27^a by an armature contact 29 or 29^a of a relay X or X'.

The operation of the entire apparatus thus far described is as follows: With the vehicle 70 carried apparatus in the normal position and both of the trips energized as shown; as the car or locomotive proceeds along the track in the direction of the arrow, shoe 18 engages trip T thereby forcing bar E upward 75 and moving bar F to the left to open the circuit controller G, thereby disrupting the main circuit for relay R. The opening of the main circuit, however, does not deenergize relay R as relay R' is now energized, 80 thus closing the secondary circuit for relay R. The circuit for relay R' may be traced as follows: from source of current 27, through contact 29, wire 28, trip T, contact shoe 18, contact finger 19, wire 26, relay R', 85 through the frame of the car or locomotive, to ground, and back to source of current 27. The energization of relay R' also energizes slow release relay R'', thereby energizing relay R through the auxiliary circuit including contact r'', wire 35, wire 31 and relay R. Should the shoe 18 fail to make a continuous contact during engagement with the trip, the auxiliary circuit for relay R will remain closed for a predetermined length of 90 time after R' is deenergized by virtue of the slow action of relay R'' in releasing its contact, and thereby maintaining relay R continuously energized in case of intermittent contact between contact shoe 18 and rail T. 100 As the relay R is maintained energized while the car is passing over trip T, it will be evident that the solenoids M and M' are maintained energized to prevent sounding of the whistle W or opening of the valve V. 105 As the car proceeds along the track, shoe 18 passes off of trip T whereby such shoe is moved to its projected position because of the action of spring 16. Simultaneously with the return of shoe 18, bar F returns to 110 its normal position, thus closing the main circuit for relay R. Thus the car proceeds at unretarded speed to engage the advance trip T', but as this trip is also energized, the vehicle governing apparatus remains in 115 effective as with the first trip.

Assume now that the trip T is deenergized when the car traverses such trip. Under this condition, the main circuit for relay R is broken as before, but the secondary circuit is not completed as relay R' is not energized; consequently, relay R becomes deenergized, thereby opening contact r and deenergizing both solenoids M and M'. The deenergization of solenoid M' causes whistle 125 W to blow thus giving an indication to the operator of the car or locomotive of certain traffic conditions in advance as will be more fully explained hereinafter. Deenergization of solenoid M, however, does not open the 130

valve V as the left-hand movement of the bar F is timed so that shoulder 23 of bar F is past the end of lever 22 before the relay R has been deenergized by the opening of 5 contact 25 so that when the solenoid M is deenergized, the lever 22 rests upon the upper surface of bar F, thus preventing bar F from actuating such lever to open the valve. After the contact shoe 18 passes off 10 of the trip T, the circuit controller G is again closed because of the spring 16, to complete the primary circuit for relay R. But owing to the slow pickup action of the relay R, the contact r of such relay is closed 15 only after the expiration of a predetermined time interval, so that the circuit for solenoids M and M' remains open during such time interval to sound the whistle W but not to apply the brakes. 20 Now assume that the second trip T' is deenergized. If the speed of the car or locomotive is such that the contact r is closed before the car reaches trip T', the car will not receive a brake application. Should the 25 car reach trip T' before contact r is closed, however, lever 22 now being in the path of shoulder 23, such lever is moved by bar F, when the shoe 18 engages trip T' to open valve V and thereby cause an application of 30 the brakes.

It will thus be seen that a car or locomotive traveling above a given speed does or does not receive a brake application according as both trips are deenergized or energized. Furthermore, it will be seen that by virtue of this control, should one of the trips be deenergized while the other is energized, the whistle W will be blown irrespective of its speed.

40 Referring now to Fig. 2, I have here shown a stretch of railway track K over which traffic normally moves in the direction of the arrow. The stretch K is divided into block sections, N—O, O—P, P—Q, etc., 45 by means of insulated joints 60, 60, etc., each block section being provided with a track circuit including a battery 61 connected across the track rails of the block section adjacent the exit end thereof, and a track relay 62 connected across the track rails adjacent the entrance end thereof. In this instance each block section is provided with two pairs of trips T and T' located at one side of the stretch K. The first pair of 50 trips, that is, the pair which is first engaged by a car or locomotive traveling in the direction of the arrow, is located at braking distance for maximum speed from the exit end of the block section, while the second pair of trips is located at braking distance for a medium speed from the exit end of the block section, as determined by the permissible speed past the first pair of trips. It will be noted that the trips of the first pair are 55 spaced from each other a relatively greater

distance than the trips of the second pair. The spacing of the first pair of trips is such as to permit the passage of a car past trip T' of such pair at a medium speed, say 35 miles per hour, without receiving a brake 70 application, while the spacing of the second pair of trips permits a car to pass trip T' of this pair at a minimum speed, say ten miles per hour without receiving a brake application. The trips T and T' of the first pair and the first trip T of the second pair are connected by wires 63, 64, and 65 respectively to a wire 66. The forward end of the wire 66 is connected to a contact 67 of relay 62 for the block section next in advance, and the rear end of wire 66 is connected to the upper point of a contact 68 of relay 62. Contact 67 of each relay 62 is connected through its upper point to one side of a battery 69, the other side of such 85 battery being grounded as shown. Trip T' of the second pair of trips for each block section is connected by a wire 70 to contact 68 of the relay for the block section next in advance. 90

For visibly controlling traffic over the stretch K, a signal S is located at the entrance end of each block section such signal being, in this instance, of the semaphore type and having three positions indicating 95 "proceed," "caution," and "stop" respectively. Each signal is controlled automatically to indicate traffic conditions in advance, in a manner well understood in the art; but as the controlling means forms no part of 100 the present invention, the same has been omitted from the drawings.

The operation of the entire system is as follows:

As shown diagrammatically in Fig. 2, the 105 block section P—Q is occupied by a car or locomotive H. With block section P—Q occupied, relay 62 for that section is deenergized and its contacts 67 and 68 are opened, thus disconnecting from their respective batteries all of the trips in block section O—P and the last trip T' for block section N—O. Assume now that a car in block section N—O approaches the second pair of trips for that block section, and that this car is 110 equipped with the vehicle governing apparatus shown in Fig. 1. The car upon engaging trip T of this pair is not affected by such trip as the latter is energized. However, when the car engages the second trip T', such trip being deenergized, the whistle is blown but the brakes are not applied. In addition to the sounding of whistle, the operator of the car is also warned by the adjacent signal S, as such signal now indicates 115 "caution." As the car enters block section O—P, relay 62 for that section is deenergized thereby opening its contacts 67 and 68 so that all of the trips for block section N—O are deenergized. As the car proceeds along 120

125 130

the stretch, it engages trip T of the first pair of trips for block section O—P, which trip being deenergized causes the whistle W to again sound. Now if the speed of the car in moving from trip to trip is above the permissive speed of thirty-five miles per hour, the brakes will be applied upon encountering trip T', thereby bringing the car to a stop. If the speed of the car is below 10 35 miles per hour, the whistle will stop blowing and magnet M will be energized before striking trip T'. When the car engages trip T', the whistle will be again blown, but the brakes will not be applied. 15 The car may thus proceed along the track to encounter the second pair of deenergized trips.

As the permissive speed set by these trips is only ten miles per hour, it will be evident 20 that should the car exceed this minimum speed between trips, it will receive a brake application subsequent to the usual sounding of the whistle W. Thus the car is prevented from entering the occupied block section P—Q at a speed greater than the predetermined minimum speed, and the engineer is warned of his approach to an occupied block by two blasts of the whistle at each trip location. 25

30 Although I have shown and described only one form of speed controlling apparatus embodying my invention, it is understood that various changes and modifications may be made therein within the scope of the 35 appended claims without departing from the spirit and scope of my invention.

Having thus described my invention, what I claim is:

1. In combination, two spaced trips located in a trackway, a member on a vehicle moved by each trip, a second member on the vehicle, a normally energized magnet on the vehicle for holding said second member out of the path of the first member, 40 means controlled by the movement of the first member by said first trip for deenergizing said magnet to permit the second member to move into the path of the first, slow-acting means set into operation by the return of the first member after operation by 45 the first trip for again energizing said magnet after a predetermined interval of time, and vehicle governing means actuated by said second member when the latter is operated by the first member.

2. In combination, two spaced trips located in a trackway, a member on a vehicle moved by each trip, a second member on the vehicle, a slow pick up relay, means controlled by said relay when energized for holding said second member out of the path of the first, means for deenergizing said relay when said first member is moved by the first trip and for again energizing said relay when the first member returns, and ve-

hicle governing means actuated by said second member when the latter is operated by the first member.

3. In combination, two spaced trips located in a trackway, a member on a vehicle moved by each trip, a second member on the vehicle biased to such position as to be operated by the first member, normally energized slow-acting electromagnetic means for holding said second member out of operative 70 position, means for deenergizing said electromagnetic means when said first member is moved by a trip and for again energizing said means when the first member returns, and vehicle governing means actuated by 75 said second member when the latter is operated by the first member.

4. In combination, two spaced trips located in a trackway, a member on a vehicle moved by each trip, a second member on the vehicle biased to such position as to be operated by the first member, normally energized slow-acting electromagnetic means for holding said second member out of operative 80 position, means for deenergizing said electromagnetic means when said first member is moved by a trip unless the trip is energized, and for again energizing said means when the first member returns, means for at 85 times energizing each trip to prevent release of the second member, and vehicle governing means actuated by said second member when the latter is operated by the first member.

5. In combination, two spaced trips located in a trackway, a member on a vehicle moved by each trip, a second member biased to such position as to be operated by the first member, a slow pick-up electromagnetic device on the vehicle, means controlled by said electromagnetic device when the latter is 105 energized for holding said second member out of operative position, a circuit on the vehicle for the control of said electromagnetic device including a contact which is opened when the first member is moved by a trip and closed when such member returns, a slow release relay on the vehicle, an auxiliary circuit for said electromagnetic device controlled by a contact of said relay which is closed when the relay is energized, 110 means for each trip controlled by traffic conditions in advance for energizing said slow release relay when said first member engages the trip, and vehicle governing means actuated by said second member when the latter is 115 operated by the first member.

6. In combination, two spaced trips located in a trackway, a member on a vehicle moved by each trip, a second member biased to such position as to be operated by the first member, means controlled by said first member for releasing said second member when the first member is operated by a trip and for restoring second member to its 125 inoperative position upon the completion of a 130

given time interval following the return of the first member to its normal position, and a warning whistle set into operation when the first member is moved by a trip and 5 maintained in operation until said first member returns to its normal position.

7. In combination, a railway vehicle, vehicle-governing means thereon, spaced trips located in the trackway, a trip member on 10 the vehicle operated by each trackway trip, an operating member on the vehicle coacting with said trip member and arranged when actuated by the latter to cause operation of said governing means, an electromagnetic 15 net adapted when energized to hold one of said members out of the path of the other member, a normally energized slow pick-up relay on the vehicle, means controlled by said trip member when operated by a 20 trackway trip for deenergizing and again energizing said relay, and means for ener-

gizing said electromagnet when said relay is closed.

8. In combination, a railway vehicle, vehicle-governing means thereon, an operating 25 member for said vehicle-governing means on the vehicle, a trip member for actuating said operating member but normally disconnected therefrom, an electromagnetic device controlling said operating member to oper- 30 atively connect said operating member with said trip member, spaced trips located in the trackway, each adapted to actuate said trip member, and a slow-acting electromagnetic 35 device.

In testimony whereof I affix my signature in presence of two witnesses.

LLOYD V. LEWIS.
